(57) **CLAIM**

The ornamental design for a cover for photosensor and electric meter, as shown and described.

DESCRIPTION

FIG. 1 is a top view of the cover according to a first embodiment of the new design;

FIG. 2 is a front elevational view thereof;

FIG. 3 is a left side elevational view thereof;

FIG. 4 is a right side elevational view thereof;

FIG. 5 is a back elevational view thereof;

FIG. 6 is a bottom view thereof;

FIG. 7 is a perspective view thereof;

FIG. 8 is a top view of the cover according to a second embodiment of the new design;

FIG. 9 is a front elevational view thereof;

FIG. 10 is a left side elevational view thereof;

FIG. 11 is a right side elevational view thereof;

FIG. 12 is a back elevational view thereof;

FIG. 13 is a bottom view thereof; and,

FIG. 14 is a perspective view thereof.

In the drawings, the broken lines depict environmental subject matter only and form no part of the claimed design.

1 Claim, 4 Drawing Sheets
